UNITED STATES PATENT OFFICE.

FRANZ SACHS, OF TETTNANG, GERMANY.

PRESS MOLD FOR DENTAL PURPOSES.

Application filed December 18, 1925, Serial No. 76,310, and in Germany August 18, 1924.

My invention relates to improvements in press-molds for dental-purposes serving especially for the production of dental plates or of the whole artificial teeth made of celluloid by means of a pressing apparatus.

According to the present invention the halves of the press-mold consist each of a frame made of two parts and being hinge-like fitted together with the ends of said parts, which parts may be united by inserting a removable pivot into the bores of the hinges disposed at both sides and closed each on their outside by means of a cap or cover. The bores for the pivots and the latter themselves are correspondingly conically shaped in such a manner, that the bores of the upper frame, which taper to the bottom, are made slightly wider than the bores of the lower frame running also conically in the same direction, so that in applying a piece of metal to the inner pivot of the lower frame the stronger pivot disposed opposite to the latter in the upper frame may be simultaneously knocked or forced out.

It is advantageous to shift the cover or cap which closes the press-mold from below by means of dove-tailed grooves sliding on corresponding ribs provided on two edges of the frame parts of the press form. In order to secure the caps and the bottom in their shifted up position the grooves and ribs, gripping into each other, are shaped 35 wedge-like to the rear, so that both parts are fixed or keyed by means of a slight knock carried out in one direction and released again by a slight knock in the other direction.

40 In the drawing the subject matter of the invention is represented by two different modes of constructions.

45 Figs. 1 to 3 show a plan view, a side elevation and a vertical sectional view of one mode of construction and Figures 4 to 7 show a second mode of construction, namely:

Fig. 4 a plan view of the frame parts,

50 Fig. 5 a sectional view through the cover respectively through the bottom,

Fig. 6 an inside view of a cover or bottom, and

55 Fig. 7 the right half in side elevation and the left half in section through the joined frame-parts of the press-mold.

According to the mode of construction

shown in Figs. 1 to 3 the frames of the press-mold consist of two parts *a*, *b*, which are hinged together by their ends. Into the preliminary bored, advantageously slight conical holes *c* of the hinges suitable pivots *d* are inserted, by means of which the frames are closed in themselves. These pivots *d* are advantageously measured in their width in such a manner that they are in the one frame, for instance in the upper one, slightly larger in their diameter than in the other one. As the bores *c* of the hinges are disposed in both frames exactly opposite one another, the pivots *d* situated directly one opposite to another, can be—if the wider bores in the upper frame and the narrower bores in the lower frame part are tapered to the bottom—driven out from below comparatively easily by means of applying a piece of metal to the thinner pivot of the lower frame without that it becomes necessary to open the press-mold.

The caps or cover plates *e*, which are advantageously slightly hollowed out on their inner sides, fit with their edges *f*, possibliest exactly into the closed frames, so that any displacing of the covers during the pressing operation cannot take place.

In order to secure the proper position of the two frames upon one another, guiding pins *g* are provided on the one frame, which during the uniting of the parts of the press-mold fit into bores *h* of the other frame.

For the escaping of superfluous celluloid mass during the pressing operation semi-circular recesses *i* facing each other are provided in a known manner on the sides of the frames that is to say in the edges of the latter on points facing each other.

The new press-molds may be produced according to requirement, in different sizes and some of the stated measurements may be replaced by similar ones.

Thus for instance instead of inserting the covers *e* with its edges *f* into the closed frame they may be attached by means of guiding pins or shifted by means of dove-tailed grooves from the side upon the frame parts.

In the mode of construction according to Figs. 4 to 7 the press-mold also consists of the upper and lower frame parts, which are made each for itself in two parts *a*, *b*, the same being united with each other by means of hinges. In the like manner there

is provided for the closure of the press-mold comprising two halves each consisting of a two part frame, the parts of which being fitted hinge-like together with its ends, said frame being enabled to be united by inserting removable pins into the bores of the hinges situated at both sides of the frame and to be closed against the outside by means of covers being fitted to the frames, the bores for the hinge-pins as well as said pins themselves being correspondingly slightly conically shaped in such a manner that the bores of the upper frame tapered to the bottom are made slightly wider than the bores of the lower frame running also conically in the same direction, so that after applying a piece of metal or the like to the weaker pin, the stronger pin being situated opposite to the same in the other frame can be knocked or forced out.

5 10 15 20 25 30 35 40

is provided for the closure of the press-mold comprising two halves each consisting of a two part frame, the parts of which being fitted hinge-like together with its ends, said frame being enabled to be united by inserting removable pins into the bores of the hinges situated at both sides of the frame and to be closed against the outside by means of covers being fitted to the frames, the bores for the hinge-pins as well as said pins themselves being correspondingly slightly conically shaped in such a manner that the bores of the upper frame tapered to the bottom are made slightly wider than the bores of the lower frame running also conically in the same direction, so that after applying a piece of metal or the like to the weaker pin, the stronger pin being situated opposite to the same in the other frame can be knocked or forced out.

45 50 55 60 65 70 75 80 85

is provided for the closure of the press-mold comprising two halves each consisting of a two part frame, the parts of which being fitted hinge-like together with its ends, said frame being enabled to be united by inserting removable pins into the bores of the hinges situated at both sides of the frame and to be closed against the outside by means of covers being fitted to the frames, the bores for the hinge-pins as well as said pins themselves being correspondingly slightly conically shaped in such a manner that the bores of the upper frame tapered to the bottom are made slightly wider than the bores of the lower frame running also conically in the same direction, so that after applying a piece of metal or the like to the weaker pin, the stronger pin being situated opposite to the same in the other frame can be knocked or forced out.

90 95

I claim:—

1. Press-mold for dental purposes especially for the production of dental plates or of the whole artificial teeth made of celluloid by means of a pressing apparatus comprising two halves each consisting of a two part frame, the parts of which being fitted hinge-like together with its ends, said frame being enabled to be united by inserting removable pins into the bores of the hinges situated at both sides of the frame and to be closed against the outside by means of covers being fitted to the frames.

2. Press-mold for dental purposes especially for the production of dental plates or of the whole artificial teeth made of celluloid by means of a pressing apparatus

3. Press-mold for dental purposes especially for the production of dental plates or of the whole artificial teeth made of celluloid by means of a pressing apparatus comprising two halves each consisting of a two part frame, the parts of which being fitted hinge-like together with its ends, said frame being enabled to be united by inserting removable pins into the bores of the hinges situated at both sides of the frame and to be closed against the outside by means of covers fitted to the frame, two edges of the same, lying opposite each other on the lower side of the flat cover and on the upper side of the bottom, being provided with lateral ledges having dovetailed recesses which at the attaching of the cover and of the bottom surround the appertaining ribs of the frame and are slightly wedge-like broadened to the rear together with the ribs, so that the cover and the bottom can be attached to the frame parts in such a manner as to be secured in their closing positions.

FRANZ SACHS.
